UNITED STATES PATENT OFFICE.

JOHN WICKS, OF CHICAGO, ILLINOIS, ASSIGNOR TO AUTOMATIC ELECTRIC COMPANY,
OF CHICAGO, ILLINOIS, A CORPORATION OF ILLINOIS.

AUTOMATIC TELEPHONE SYSTEM.

Application filed October 23, 1920. Serial No. 418,944.

To all whom it may concern:

Be it known that I, JOHN WICKS, a citizen of the United States of America, and a resident of Chicago, Cook County, and State 5 of Illinois, have invented certain new and useful Improvements in Automatic Telephone Systems, of which the following is a specification.

This invention relates in general to automatic telephone systems, but more especially to automatic party line systems of the type 10 commonly known as "semi-selective," in which each party line has two "one bell" stations and two "two bell" stations connected from opposite sides of the line to ground; and the object of the invention, 15 stated broadly, is to provide suitable ring back switches and associated apparatus through the medium of which any subscriber 20 on a party line can signal any other subscriber on the same line.

Ring back switches have been designed before this to handle the reverting calls in automatic party line systems, but the former 25 ringback equipments are intended to operate in other types of selective signalling systems, as for example, the well known harmonic system, and they will not operate in the particular type of selective ringing system herein 30 contemplated. New circuits have been devised, therefore, suitable for use in a party line signalling system of the "semi-selective" type, and thus a new ring back equipment is 35 produced which is adapted for use in a situation where the known ring back equipments would be of no utility.

The invention, thus briefly set forth in its essential features, will be described fully hereinafter, reference being had to the accompanying drawings, comprising Figs. 1, 40 2, and 3, wherein is shown by means of the usual circuit diagrams enough of the apparatus in a telephone system to enable the invention to be understood.

Referring now to Fig. 1, there is shown at 45 the upper left hand corner of the sheet a four party line comprising conductors 6 and 7, and automatic telephone substations 1 to 4, inclusive. Substations 1 and 3 are "one bell" stations, while substations 2 and 4 are "two bell" stations. The ringers at stations 1 and 2 are connected from line conductor 7

to ground, as indicated in the drawing, while the ringers at the two remaining stations are connected from line conductor 6 to ground. 55

At the exchange the party line terminates in an individual line or trunk selecting switch which is indicated by reference character C. The line switch C is of the well known rotary type, in which the wipers 60 have no normal position and move in a forward direction only, and in common with other similar line switches has access to a group of trunk lines leading to first selector switches. 65

One of these trunk lines is shown in the drawing and extends to the selector E, which is a switch of the usual Strowger vertical and rotary type and is operated according to the well known two wire system 70 of control, as are all the other switches in the system. The selector E has 10 levels of bank contacts and one of the levels, as, for example, the first, may be reserved for the reverting call apparatus, or ringback 75 switches. The other levels serve to give access to the different groups of second selectors.

One of the reverting call trunk lines which is accessible to the selector E and similar 80 selectors is shown as extending to the ringback switch F, Fig. 2. This switch comprises wipers 88 and 89, the stepping magnet 84, and the release magnet 160. The circuits of the switch are controlled by the 85 relays shown at the left, whose operation and function will be explained.

Cooperating with the ringback switch F and a plurality of similar ringback switches is a common mechanism shown in Fig. 3. 90 This mechanism comprises a solenoid interrupter M and a group of relays associated therewith, whose function is to project ringing current according to the proper codes over either or both conductors of a calling 95 line, the precise ringing operation performed being determined by the selective operation of the ring back switch in use. In order to enable any subscriber to initiate the proper ringing operation required to signal any 100 other subscriber on his line, code call numbers are assigned, and each subscriber is furnished with a list of the numbers pertaining to his particular station. The table below

is a complete list of all numbers required for a four party line.

Station No. 1	calling Station No. 2	dial 11
" " 1	" " 3	" 12
" " 1	" " 4	" 13
" " 2	" " 1	" 14
" " 2	" " 3	" 15
" " 2	" " 4	" 16
" " 3	" " 4	" 17
" " 3	" " 1	" 12
" " 3	" " 2	" 15
" " 4	" " 3	" 18
" " 4	" " 1	" 13
" " 4	" " 2	" 16

15 The subscribers at stations 1 and 3 are instructed to respond to one long ring and the subscribers at stations 2 and 4 are instructed to respond to two short rings.

20 I will now describe the different signalling operations which may be performed, it being assumed first that the subscriber at station 1 desires to call the subscriber at station 2.

When the receiver is removed from the 25 switch-hook preparatory to making a call, a circuit is closed for the line relay 5 over the line conductors 6 and 7 in the well known manner. Line relay 5 energizes and completes a circuit for switching relay 8 at 30 armature 9, and at armature 10 connects the private wiper 12 to the above circuit at a point midway between the switching relay and the motor magnet. Because of the fact that the trunk selecting operation of the 35 lineswitch C is well known, we will assume that the trunk line upon which the wipers 11 to 13, inclusive, are resting is idle. Under these circumstances relay 8 will energize immediately after line relay 5 has operated, 40 with the result that the line conductors 7 and 6 are disconnected from the winding of line relay 5 and ground, respectively, and are extended by way of armatures 14 and 15 and their working contacts, wipers 11 and 13, 45 bank contacts 16 and 17, and armatures 18 and 19 and their resting contacts to the upper and lower windings of line relay 25 of selector E.

As soon as the line is extended to selector 50 E, as above described, the line relay 25 will be energized and will operate to close the circuit of slow acting release relay 26.

Upon energizing, the latter relay prepares the vertical magnet circuit at armature 29 55 and its front contact, and at armature 27 and its front contact places ground G² on conductor 28, thereby establishing a holding circuit which extends by way of bank contact 20, wiper 12, armature 21 and its front 60 contact, winding of switching relay 8 and the stepping magnet to battery. It will be understood that the above traced holding circuit is completed before the slow acting line relay 5 has deenergized. Besides maintaining the switching relay energized, this

holding circuit serves to place ground on multiples of test contact 20, and also on the multiple test contacts in which the private normal conductor 22 terminates in the banks of connector switches which have access to 70 the party line, thus guarding the connection from intrusion in the ordinary manner.

The calling subscriber may now operate his calling device S in accordance with the first digit of the desired number, which in 75 this case is the digit 1. One interruption is thereby produced in the circuit of line relay 25, which on retracting its armature completes a circuit for vertical magnet 30 in series with slow acting relay 29. By the 80

operation of the vertical magnet the shaft carrying the wipers 35 to 37, inclusive, is raised opposite the first level of bank contacts, in which trunk lines leading to the ringback switches terminate. The slow acting relay 29 is energized in series with the vertical magnet and upon the first vertical step of the shaft, off normal springs 41 and 42 having closed, a circuit is completed from ground on conductor 28 by way of armature 43 and its front contact, off normal springs 42, and the winding of relay 44 to battery. This latter relay, on attracting its armature 46, completes a locking circuit for itself, and also prepares the circuit of rotary magnet 50. At end of the vertical movement of the switch, relay 29 deenergizes and closes the circuit of rotary magnet 50 which operates to advance the wipers 35 to 37, inclusive, 90 into engagement with the first set of bank contacts in the first level. The rotary magnet 50 also breaks the locking circuit of relay 44 which accordingly deenergizes and breaks the circuit of the rotary magnet, which also deenergizes. The further operation of the 95 switch depends on whether or not the first trunk line is busy or idle. If busy, the test contact engaged by wiper 36 will be grounded, and a circuit is completed from the 100 grounded test contact by way of wiper 36, conductor 49, springs 48, springs 42, and relay 44 to battery. Relay 44 therefore 105 again operates to again close the rotary magnet circuit. The alternate operation of relay 44 and rotary magnet 50 will continue until an idle trunk is found, which we will assume is the trunk line terminating in bank contacts 38, 39, and 40. No ground will be present on the bank contact 39 when engaged by wiper 36 and relay 44 therefore 110 will not again pull up, but relay 51, which is no longer shorted, will energize in series with relay 44 in the usual manner. Upon 115 energizing relay 51 disconnects the incoming line conductors from the windings of line relay 25 and extends them by way of armatures 18 and 19 and the front contacts, wipers 35 and 37, bank contacts 38 and 40, 120 trunk conductors 54 and 56, armatures 60 and 61 and their resting contacts, and the 125

130

upper and lower windings of line relay 75 of ring back switch F to battery and ground, respectively.

Relay 75 on attracting its armature completes the circuit of slow acting release relay 76, which prepares the rotary magnet circuit at armature 77, and places ground G⁴, at armature 78 and its front contact, on conductor 55 extending back to switching relay 51 of selector F, and switching relay 8 of lineswitch C, to hold these relays in their operated position.

The subscriber at station 1 may now operate his calling device for the last digit of the number, which in this case will also be the digit 1, thereby producing one interruption in the circuit of line relay 75. On retracting its armature, relay 75 completes a circuit from ground G⁵ by way of armature 79 and its back contact, armature 77 and its front contact, conductor 80, armature 81 and its back contact, conductor 83, and the rotary magnet 84 to battery, there being a branch circuit in multiple with the above which extends through the slow acting relay 85 to battery. When its circuit is closed the rotary magnet 84 operates to rotate the shaft carrying wipers 88 and 89 on to the first set of bank contacts 90 and 91 in an obvious manner. On the first rotary step of the switch off normal springs 92 and 99 close. Relay 85 is energized in parallel with the rotary magnet and when this relay falls back, an instant after the impulse to the rotary magnet has been sent, a circuit is completed from ground on conductor 94 by way of springs 92, back contact and armature 95, and the winding of relay 96 to battery. Relay 96, upon energizing, locks itself at armature 97, and at armature 81 opens the rotary magnet circuit.

No further operation of the ringback switch will take place until the calling subscriber hangs up his receiver, thus opening the circuit of line relay 75. Relay 75, on retracting its armature, opens the circuit of slow acting relay 76 and also, before relay 76 deenergizes, sends an impulse of current to slow acting relay 85, which energizes. When relay 76 falls back it will break the circuit of relay 85 but before the latter relay has time to deenergize a circuit is closed which extends from ground G⁵ by way of armature 79 and its back contact, armature 77 and its back contact, armature 98 and its front contact, and through the winding of relay 100 to battery. On attracting its armatures this relay locks itself over a circuit extending from ground G⁶ by way of armature 101 and its front contact, conductor 94, armature 101 and its back contact, conductor 103, and armature 104 and its front contact, and through relay 100 to battery. This ground also extends over conductor 55 to switching relays 51 and 8 of selector E and

line switch C, respectively, to maintain these switches in their operated positions. After slow acting release relay 76 had deenergized and before relay 100 energized these preceding switches were held up by ground from the armature of slow acting relay 85, which deenergizes shortly after the energization of relay 100. Relay 100 also closes a circuit extending from ground G⁷, through armature 109 and its front contact, conductor 110, and the winding of relay 111 to battery. Relay 111 attracts its armature and places battery, at armature 112 and its front contact, on conductor 113, which extends by way of wiper 114, and the winding of solenoid 115 of the solenoid interrupter M to ground.

This solenoid interrupter is the ringing interrupter, whose operation will be briefly described before continuing with the circuit explanation. When the winding 115 energizes the solenoid pulls up its plunger 117 carrying wiper 123 at once, and upon the wiper reaching the top contact 125 the pin 118 will move the arm 120 into its alternate position, thus opening the contact at wiper 114. The wiper will remain in this position until pin 121 moves the arm 120 into its original position, this occurring when the shaft is again normal. The plunger arm 117 is so constructed that while it will be pulled up rapidly by winding 115 its return to normal will take an appreciable time, the slow descent being accomplished in any well known manner, as by means of a dashpot. The upward movement of the wiper 123, although ground is placed successively on the ringing relays, takes place so fast that none of the relays are operated.

Returning again to the ringing operation, upon the wiper 123 engaging contact 125 in its downward motion a circuit is completed from ground G¹⁰, through contact 124, wiper 123, contact 125, conductor 126, winding of relay 127, and conductor 128 to battery. Relay 127 will energize and at armature 131 and its front contact, place ground G⁹ on conductor 132 extending through armature 133 and its front contact, and the winding of relay 134 to battery. This latter relay, on attracting its armature, locks itself to ground on conductor 55 and completes the ringing circuit for the called subscriber's telephone, extending from the ungrounded pole of generator G, conductor 135, front contact and armature 129, conductor 130, bank contact 90, wiper 88, ring cut off relay 136, conductor 137, front contact and armature 60, conductor 54, bank contact 38, wiper 35, front contact and armature 18, bank contact 16, wiper 11, front contact and armature 14 to line conductor 7, thence through the ringers of substations 1 and 2, on the party line, to ground. The ringers at both substations respond for a short interval but the circuit is soon broken because the inter-

rupter M on passing to the next contact breaks the circuit for relay 127, which retracts its armature and opens the above traced ringing circuit. Relay 136, the ring 5 cut off relay, is so adjusted that it will not respond to alternating current but will energize when direct current flows through its winding. Upon wiper 123 engaging contact 141 a circuit is completed for relay 139 from 10 ground G¹⁰. Relay 139 energizes and at armature 145 places ground on conductor 150 extending to bank contact 151, and at armature 146 places generator on conductor 152 extending to bank contact 153 but since 15 the wipers 88 and 89 of the ring back switch are not in engagement with this set of bank contacts the operation of relay 139 has no effect at this time. Now upon the contactor 123 reaching contact 154 ground is placed on 20 conductor 155 extending through 140 to battery. On energizing, relay 140 at armature 142 again places generator on conductor 130 and thus reestablishes the ringing circuit extending back to substations 1 and 2. This 25 will operate the ringers there for another short period. Two short rings is the call signal of two bell station 2 and the subscriber thereat will know that he is being called. The bell at substation 1 will also 30 be actuated and the calling subscriber thereat is thus notified that the apparatus is working properly and that the subscriber at station 2 is being signalled.

As the plunger arm of the solenoid inter- 35 rupter descends ground will be placed successively on contacts 156 and 157 and relays 158 and 160, and 189 and 160, will be operated, but their operation will have no effect at this time. Upon the plunger arm 117 40 reaching its normal position, pin 121 moves arm 120 into its normal position thereby again closing the circuit for the solenoid winding 115. This same ringing operation as heretofore described is then repeated and 45 will continue until the subscriber at substation number 2 removes his receiver, thereby permitting direct current to flow over the previously traced ringing circuit to the subscriber's telephone (not shown, but exactly 50 like the telephone at station 1), then through switch-hook springs receiver and transmitter to line conductor 6, thence over a circuit similar to the one above traced to wiper 89 of the ringback switch, and thence 55 by way of bank contact 91 to ground. Had subscriber at station 2 removed his receiver during a silent period the circuit for relay 136 would be completed from battery B' on conductor 190 instead of from battery B at 60 the ringing generator. Relay 136 will energize, opening the locking circuit of relay 100 at armature 102. Relay 100, on deenergizing completes the circuit for the release magnet 160 this circuit extending from ground 65 G⁵, armature 79 and its back contact, arma-

ture 77 and its back contact, armature 98 and its back contact, armature 188 and its back contact, off normal springs 99, conductor 159, and the winding of release magnet 160 to battery. Magnet 160 will operate to restore the switch to its normal condition. Upon retracting its armature 101, relay 100 removes ground from conductor 55 extending back to switching relays 51 and 8 of selector E and lineswitch C, and also removes the ground from conductor 110 at armature 109 which has hitherto maintained ringing interrupter M in continuous operation. Switches E and C are thus released and the operation of the interrupter M is stopped. 70 75 80

When the selector E and lineswitch C are restored, relay 8, on deenergizing, again completes the circuit of line relay 5 of lineswitch C, as the subscriber at station 2 has his receiver off the switchhook, and a circuit is again closed for relay 8, which operates as before to extend the line conductors to the upper and lower windings of line relay 25 of selector E. 90

As subscriber at station 1 no longer hears the ringing of his bell he will know that the subscriber at station 2 has responded, whereupon he will remove his receiver also. Conversation may now take place over the heavy line conductors of the line between the two stations, battery being supplied from the upper and lower windings of line relay 25. When the conversation is terminated the release of the switches will take place, upon 100 the subscribers replacing their receivers on the switchhook, in an ordinary manner. Had the subscriber at station 2 not responded the subscriber at station 1 upon removing his receiver would cause the ringing operation to cease and the release of the switches would take place when the receiver was replaced. 105

I will now briefly describe the operation of the apparatus when the subscriber at 110 station 1 calls the subscriber at station 4, a party whose ringer is connected from the opposite side of the line to ground and who is instructed to respond to 2 short rings. To make this call it will be seen from the 115 table shown hereinbefore, that the number the subscriber at station 1 will dial will be 13. The operation of the lineswitch C, first selector E and ring back switch F is the same as hereinbefore described, except that instead of one impulse being sent to rotary magnet 84 of the ringback switch F, three impulses will be sent and wipers 88 and 89 will be rotated into engagement with the 120 third set of bank contacts. The solenoid interrupter M and relays will operate as before described but a different group of relays will supply the ringing current to the party line, because wipers 88 and 89 are now resting on the third set of bank contacts. These 125 130

operations will doubtless be clear but may be briefly described nevertheless. When contactor 123 of the solenoid interrupter engages contact 125 a circuit is completed for relay 127 in an obvious manner, and this relay closes the circuit of the pick up relay 134 at armature 131. At armature 161, generator is placed on conductor 162 and a circuit is closed by way of bank contact 163, 5 wiper 89, the lower heavy line conductor and through the ringers of substations 3 and 4 to ground. Now as soon as wiper 123 disengages contact 125, relay 127 deenergizes opening the above traced ringing circuit. 10 15 When contactor 123 engages contact 154 a circuit will be completed for relay 140, which on energizing again connects generator to conductor 162 and thence to the ringers of substations 3 and 4 whose bells 20 will be again actuated for a short period. Thus two short rings will be produced at two bell substation 4. Upon wiper 123 engaging contact 156 a circuit for relay 189 is completed. This relay on attracting its 25 armature 188 closes the circuit of relay 160. This latter relay on attracting its armature 189' places generator on conductor 164, and closes a ringing circuit extending by way of bank contact 165, and wiper 88 to the upper 30 side of the line, whence it goes through the ringers of substations 1 and 2 to ground. As soon as wiper 123 of solenoid M reaches 35 contact 157 a circuit is completed for relay 158, which on energizing places ground on conductor 166 extending to relay 160 to maintain this relay energized. The circuit through relay 158 is closed before the circuit of relay 189 is broken and thus the ringer at station 1 will be actuated for one long 40 ring to notify the calling subscriber that his call is proceeding satisfactorily. This ringing of the called and calling subscribers will continue alternately until the subscriber at station 4 answers whereupon the operation 45 will proceed as herein before described.

Should the wipers 89 and 88 of the ring-back switch F be rotated into engagement with contacts 170 and 171 by the subscriber at station 1 or the subscriber at station 3, 50 relays 140 and 139 of the relay group will be actuated successively and as each completes the circuit of relay 183, one long ring will be sent from generator G by way of armature 180 and its front contact, conductor 181, bank contact 171, wiper 88, to the substations 1 and 2. The operation of 55 relays 189 and 158 will also be effective at this time, and as each completes the circuit of relay 160, one long ring will also be sent to substations number 3 and 4 from generator G by way of armature 189' and its front contact. Thus stations 1 and 3 would 60 be signalled.

If the wipers 88 and 89 were in engagement with bank contacts 172 and 173 then

the operation of relays 139 and 140 would be effective as before to send one long ring to substations numbers 1 and 2. This would be the case if the subscriber at station 2 were calling the subscriber at station 1. 70

If wipers 88 and 89 were on contacts 174 and 175, relays 127 and 140 would operate to send 2 short rings to stations 1 and 2 and relays 139 and 140 would operate to send one long ring to stations 3 and 4, thereby 75 signalling the subscribers at stations 2 and 3.

If wipers 88 and 89 had been rotated on to bank contacts 151 and 153, relays 127 and 140 would then operate to give two short rings to stations 1 and 2, and relays 139 80 and 158 would operate to give two short rings to stations 3 and 4. This signals the subscribers at stations 2 and 4.

Had wipers 88 and 89 been rotated into engagement with bank contacts 176 and 177, 85 the operation of relays 127 and 140 would have been effective to send two short rings to stations 3 and 4 on the party line. This would be the case if the subscriber at station 3 were calling the subscriber at station 4. 90

If the wipers had been rotated on to bank contacts 178 and 179, as where the subscriber at station 4 calls the subscriber at station 3, relays 140 and 139 in operating would be effective to energize relay 183 to send a long 95 ring to stations 3 and 4.

Having fully described and ascertained the features of this invention, what I consider to be new and desire to have protected by Letters Patent will be pointed out in the 100 appended claims.

What I claim as my invention is:

1. In a telephone system, the combination, with a party line provided with substation ringers connected from the same side of the line to ground, of a grounded ringing generator, automatic ringing equipment, automatic means controlled over said line for extending a connection to said equipment, and automatic means including said equipment for variably connecting the ungrounded pole of said generator to the ringer conductor of said line to selectively signal the parties thereon over a circuit including said extended connection. 110

2. In a telephone system, the combination, with a four party line provided with substation ringers connected from opposite sides of the line to ground, of a grounded ringing generator, automatic means controlled over said line for extending a connection to said generator, automatic means for connecting either conductor of said line to the ungrounded pole of said generator over a circuit including said extended connection, 120 and code ringing means cooperating with said generator to selectively signal all the parties on said party line. 125

3. In a telephone system, the combination, with a four party line provided with sub- 130

station ringers connected from opposite sides of the line to ground, of a grounded ringing generator, automatic means controlled over said line for connecting either conductor thereof to the ungrounded pole of said generator, and a solenoid interrupter co-operating with said generator to selectively signal all the parties on said party line.

4. In a telephone system, the combination, 10 with a party line provided with substation ringers connected from the same side of the line to ground, of a grounded ringing generator, automatic means including a ring-back switch controlled over said line for extending a connection to said generator, automatic means for connecting the ringer side of said line to the ungrounded pole of said generator over a circuit including said extended connection, and code ringing equipment 20 cooperating with said generator to selectively operate said ringers.

5. In a telephone system, a party line, a plurality of substations thereon, a ringing generator, a solenoid interrupter, and means 25 for causing said generator to apply signalling current to said party line, the said means being controlled by said interrupter according to a predetermined code to selectively signal said substations.

30 6. In a telephone system, a party line, substation ringers connected from one side of said line to ground, and ringback apparatus for enabling one party to call another on the same line, said apparatus comprising means for transmitting ringing current from a single generator over a circuit including the ringer side of said line according to predetermined codes, automatic switches whereby one party on said line may 40 establish a connection with said apparatus, and means for projecting current over said circuit and said automatic switches to selectively signal a station on said party line.

7. In a telephone system, a party line, a 45 one bell station and a two bell station on said party line, having ringers connected from the same side of said line to ground, ring back apparatus for enabling either party on said line to call the other, means 50 for extending a connection to said ring back apparatus, and means controlled by said apparatus for projecting signalling current back over said extended connection to selectively signal a station on said line.

55 8. In a telephone system, a party line, two two bell stations having ringers connected from opposite sides of the line to the ground, ring-back apparatus for enabling either of said stations to signal the other, and auto-

matic means in said ring back apparatus for 60 signalling the calling as well as the called station.

9. In a telephone system, a party line, two one bell stations on said line having ringers connected from opposite sides of the line 65 to ground, two two bell stations having ringers connected from opposite sides of the line to ground, means including a ring back switch whereby the subscriber at any station on said line can project code ringing 70 currents back over said line from the exchange to signal any other subscriber, and means for ringing the code belonging to the calling station also in case the ringers at the calling and called stations are not connected 75 to the same side of the line.

10. In a telephone system, a party line, two one bell stations on said line having ringers connected from opposite sides of the line to ground, two two bell stations having 80 ringers connected from opposite sides of the line to ground, and code ringing mechanism at the exchange controlled by any calling subscriber for signalling any other subscriber on the line, said mechanism including means for ringing the code belonging to the calling station also in case the ringers at the calling and called stations are connected to opposite sides of the line but not if the ringers are connected to the same side 85 of the line.

11. In a telephone system, a party line, stations on said line having ringers connected from opposite sides of the line to ground, ringing equipment including a grounded 95 generator, an automatic switch controlled from said line for extending a connection to said ringing equipment, automatic means controlled by said equipment for variably applying ringing current from said generator to either conductor of said line over said established connection to selectively signal the stations on said party line.

12. In a telephone system, a party line, stations on said line having ringers connected from opposite sides of the line to ground, and code ringing mechanism at the exchange controlled by any calling subscriber for selectively signalling any other subscriber on the line, said mechanism including means for ringing the calling station also in case the ringers at the calling and called stations are connected to opposite sides of the line but not if the ringers are connected to the same side of the line.

Signed by me at Chicago, Cook County, Illinois, this 19th day of October, 1920.

JOHN WICKS.
